UNITED STATES PATENT OFFICE.

HERBERT L. BROWN, OF RICHMOND, VIRGINIA.

WALL VENTILATOR.

Application filed December 18, 1925. Serial No. 76,206.

The object of this invention is to provide a simple ventilator for walls, stair-risers, etc., that will prevent the adjustment being tampered with after the ventilator is set in 5 the wall. This type of ventilator is particularly adapted for the intake or exhaust air-flues in theaters, churches, auditoriums, etc. Where it is used in a gallery, it is set in the riser. In this type of ventilator, it 10 is desirable that the damper-plate shall be locked in its adjusted position in such manner that it would be difficult for an unauthorized person to tamper with the adjustment. The damper-plate may be adjusted 15 from time to time by the use of special tools and only with more effort than would be exerted by one who was unauthorized to re-adjust the damper.

In the drawing—

20 Fig. 1 is a vertical sectional view of my improved ventilator set in place in a wall opening;

Fig. 2 is a view looking at the inner side of the ventilator.

25 Referring to the drawing annexed by reference-characters, 5 designates the usual metallic grating that is adapted to be set into the ventilating opening in the wall or riser. To the inner side of this grating, at the 30 lower edge thereof, is pivoted a damper-plate 6 which inclines upwardly and inwardly, thereby extending partly across the air-flue. This pivoted damper-plate is held in its adjusted position by means of a pivoted rack-bar 7 and a bendable lock-ear 8 carried by 35 the damper-plate.

The rack-bar is pivoted to the grating by a horizontal pivot and tends to swing downwardly at its inner free end. This rack-bar 40 extends through a slot in the damper-plate, and this slot is formed by cutting or stamping out of the damper-plate the aforesaid lock-ear 8. The parts are locked by first swinging the damper-plate to the desired po-

sition, then swinging the free end of the 45 rack-bar upwardly until the desired notch in its upper curved edge engages the top edge of the slot in the damper-plate; then the lock-ear is bent either backwardly or forwardly until it impinges against the 50 lower curved edge of the rack-bar, thereby locking the rack-bar with its notch in engagement with the damper-plate.

It will be observed that I provide a very 55 simple mechanism for locking the damper-plate semi-permanently and that the adjustment of the damper-plate can be disturbed only by manipulation of tools that would be too troublesome for one to resort to who was 60 unauthorized to change the adjustment.

What I claim as new is:

1. In a ventilator of the type set forth, a 65 grating for the opening of the air-flue, a damper-plate pivoted to one of the horizontal edges of the grating adapted to swing inwardly into the air-flue, and a notched rack-bar pivoted to the grating and extending inwardly through an elongated opening in the damper-plate, the damper-plate carrying a bendable lug adapted to be bent 70 against the edge of the rack-bar opposite the notches therein.

2. In a ventilator of the type set forth, a 75 grating adapted to be set into the opening of the air-flue, a sheet-metal damper-plate pivoted to the inner side of the grating at the lower edge thereof so as to be capable of swinging inwardly into the air-flue, said damper-plate being provided with an elongated opening, the metal formed by making 80 this opening being adapted to be used as a bendable lock-ear, and a curved notched rack-bar pivotally mounted on the grating and extending through said opening in the damper-plate.

85 In testimony whereof I hereunto affix my signature.

HERBERT L. BROWN.
